W. G. HALL

ELECTRICAL PROTECTION FOR OIL STORAGE

Filed May 3, 1926

INVENTOR
WINSLOW G. HALL
BY *Miller & Boyken*

ATTORNEY

UNITED STATES PATENT OFFICE.

WINSLOW G. HALL, OF BURLINGAME, CALIFORNIA.

ELECTRICAL PROTECTION FOR OIL STORAGE.

Application filed May 3, 1926. Serial No. 106,426.

This invention relates to a method and means for protecting oil storage reservoirs from the dangers of conflagration through static charges of electricity. The objects of 5 the invention are to provide a method and means for such protection of reservoirs which will be practicable and effective against static charges of any nature whether same be within the oil body, gas blanket or 10 surrounding media, and occasioned through frictional or induction influences or direct stroke of lightning.

Briefly stated, my method comprises surrounding and penetrating the container and 15 its contents with a great number of electrical conductors forming a single grounded system and whereby the equipotential condition of the reservoir and its contents is maintained and any unbalanced electrical 20 stresses prevented.

The drawings accompanying this application are diagrammatic representations of my system of electrical conductors applied to an oil storage reservoir, Fig. 1 being a sectional 25 elevation of an oil storage reservoir equipped as outlined above, and Fig. 2 is a plan view of the same.

In the drawings the reservoir 1 is presented as of concrete imbedded in the earth 30 2, tho it is to be understood that my system applies to oil storage reservoirs of any type or size holding a supply of any kind of oil, whether same be crude, refined, or gasoline.

The reservoir is covered by a roof 3 preferably of wooden construction and which roof in large reservoirs is suitably supported in the usual way on posts not shown.

Within the reservoir passing through the body 4 of oil and grounded at their lower 40 ends, are spaced electrical conductors 5 preferably made of piping, while extending horizontally throughout the reservoir within the oil 4 and gas blanket 6 are conductors 7 also grounded at their ends and electrically secured to the vertical conductors 5 preferably by welding, tho if all are of piping, screw fittings may be used to form the joints.

An additional network of conductors is secured to the under side of the reservoir cover 50 as at 8 all welded together and to the vertical conductors 5, while the outer surface of

the cover is preferably sheathed with metal as at 9 also electrically secured to the vertical conductors 5.

The surface conductors both on the inner 55 and outer surface of the cover may consist of heavy wire mesh in place of solid sheathing if desired, and the vertical conductors 5 extending through and above the cover, or roof 3 supports an additional network of 60 conductors 10 over and beyond the entire reservoir further supported by other vertical posts, preferably grounded conductors, 11 electrically connected to the elevated network and effectively grounded at many 65 points as at 12.

By thus forming a grounded gridiron of conductors completely surrounding and penetrating everywhere the reservoir, oil body, gas blanket, and surfaces of relative- 70 ly dielectric stratas, the possibility of accumulated electrical potential; with danger of disruptive discharges; is entirely avoided either within the oil through pumping or other frictional movement, or at any point 75 through outside electrical disturbances.

I claim:

1. In the storing of oil and its liquid products, the provision of a network of grounded electrical conductors above the entire area of the reservoir, and extensions of 80 the conductors passing through the oil within the reservoir.

2. In the storing of oil and its liquid products, the provision of a network of grounded electrical conductors above the entire area of the reservoir, and extensions of the conductors passing through the oil within the reservoir, and an additional layer of conductors on the roof of the reservoir electrically connected to the aforesaid conductors. 85

3. In the storing of oil and its liquid products, the provision of a network of grounded electrical conductors above the entire area of the reservoir, and extensions of the conductors passing through the gas blanket and 90 oil within the reservoir, and additionally grounded through the reservoir so as to

bring all to substantially equipotential condition. 95

WINSLOW G. HALL.
